TREATMENT OF HYDROCARBON OIL

George Armistead, Jr., Scarsdale, N. Y., assignor
to Gasoline Products Company, Inc., Newark,
N. J., a corporation of Delaware

Application September 30, 1937, Serial No. 166,492

3 Claims. (Cl. 196—67)

This invention relates to the art of converting higher boiling hydrocarbons into lower boiling hydrocarbons.

According to my invention the heat necessary to effect the desired extent of cracking of a heavy oil and drastic cracking of a relatively clean oil is supplied by burning a residual oil or the like and mixing the hot products of combustion directly with the oils to be cracked so as to utilize a substantial part of the heat thus generated. One of the reasons why prior processes in which air is injected into a large body of oil in a large vessel have not been successful is because of the objectionable deposition of coke. In one step of my process the oil and oxygen-containing gas are passed through a narrow and confined passage-way, and in this way objectionable coking is overcome as there is a continual movement of oil past the nozzle. My invention may also employ an oxygen-containing gas richer in oxygen than air, in fact, pure oxygen itself and with the presence of less inert diluent gas at the point of combustion, higher localized temperatures are obtained with consequent improvement in oil de-

25. composition rate and character of products.

In one form of the invention a heavy oil is burned with oxygen or with an oxygen-containing gas and the hot products of combustion, preferably separated from unburned heavy oil, are directly mixed with a relatively clean oil stock to be cracked to raise the temperature of the clean oil stock to an active cracking temperature. The combined stream is then passed through a cracking coil or zone wherein the oil to be cracked is maintained under superatmospheric pressure and a high temperature for a sufficient time to effect the desired cracking.

40 The stream of cracked products leaving the cracking zone is then passed under a lower pressure to an evaporator or separating zone where hot vapors are separated from cracked residue. Before being passed to the evaporator, the stream of cracked products may be mixed with products coming from another cracking zone as will be hereinafter described. The hot vapors pass upwardly in the evaporator or separating zone and are contacted with a relatively heavy fresh charging oil, such as reduced crude oil, and in this way some of the hot vapors are condensed to form a heavy reflux condensate and some of the lighter constituents of the relatively heavy oil are vaporized.

45 The unvaporized fractions of the heavy charging oil and the heavy reflux condensate are collected and a portion thereof may be burned with

5 oxygen or with an oxygen-containing gas, there being insufficient oxygen to consume all of the oil. By this combustion the temperature of the heavy oil and reflux condensate is raised and the heavy oil and reflux condensate are subjected to any degree of cracking varying from a mild conversion directed at the reduction of viscosity and formation of gas oils from the residuals to the formation of a large yield of gasoline. The products of this treatment are discharged into a separator in which they may be separated into vapors and a liquid residue. The vapors are passed to the evaporator or separating zone above mentioned and the liquid residue under reduced pressure is mixed with the stream of cracked products leaving the first mentioned cracking zone, the latter combined stream also being introduced into the evaporator or separating zone above described. However, the separator may be bypassed and all the products of this treatment may be mixed with the cracked products leaving the first mentioned cracking zone and the combined stream then passed to the evaporator or separating zone.

10 The vapors remaining after contact with the relatively heavy charging oil are fractionated to separate a reflux condensate of the nature of gas oil from vapors of the desired boiling range. The gas oil condensate thus separated may form the feed stock to the clean oil cracking zone herein- 15 before mentioned. The vapors of the desired boiling range are further treated to separate water and carbon dioxide from the gasoline product in any suitable manner.

20 In the drawing I have shown a diagrammatic flow sheet of apparatus adapted for practicing my invention.

25 Referring now to the drawing, the main parts of the apparatus comprise a combustion chamber or zone 10, a cracking zone 12, another cracking zone 14, a combined evaporator and fractionating zone 16 and a secondary fractionating zone 18 which may be of bubble tower construction. Pipe lines, pumps and other means are included whereby the methods of my invention may be carried out. The heavy oil collecting at the bottom of the combined evaporator and fractionating zone 16 comprises cracked residue as will be later described in more detail. The cracked residue is withdrawn through line 22 and a portion thereof is passed through line 24 by pump 26 and introduced into the combustion zone 10 where it is mixed and burned with oxygen or an oxygen-containing gas introduced through line 28 by pump 32. By regulating the opening of

valve 33 any desired portion or all of the heavy cracked oil passing through line 22 may be pumped through line 24.

The heavy oil is burned during its passage through the combustion zone 10 which is of proper construction to obtain the desired contact between the oil and oxygen or oxygen-containing gas and to permit the required burning. Types of combustion zones may include nozzle mixers, refractory lined extended passages or the like. The proportion of oil to oxygen may be such that a portion or all of the oil is consumed. The hot vapors and products of combustion thus formed may be passed through line 34 to a separator 35 wherein any liquid residue is separated from hot products of combustion and is withdrawn through line 36, the vaporous products and gases of combustion being passed through line 38. However, the separator 35 may be omitted, if desired, in which case all of the products leaving the combustion zone 10 are then passed through line 38. Where all the oil introduced into zone 10 is burned, high temperatures are obtained and it will be necessary to construct the separator 35, if one is used, and lines 34 and 38, as well as the zone 10, of refractory material to withstand such high temperatures. In addition I may cool the hot products of combustion in the zone 10 by introducing cool gases through line 39, the gases being recovered during the operation of the process as will be later explained. Or the separator 35, lines 34 and 38 and the zone 10 may be internally insulated to protect the internal surfaces thereof from the high temperatures.

A relatively clean oil stock such as condensate oil taken from the bottom of the secondary fractionating zone 18, is passed through line 40 by pump 41 and is admixed with the hot products of combustion passing through line 38 in order to immediately raise the clean oil stock to an active cracking temperature. The heated oil is then passed through the cracking zone 12 preferably unfired where it is maintained under high temperature and high pressure conditions in order to effect the desired cracking. The cracking zone may also include a soaker 42 but this soaker may be of coil construction and form a continuation of the cracking coil or zone 12. In some instances it may be desirable to provide a furnace or heater for the cracking coil or zone 12 and soaker 42 if a coil is used to supply additional heat externally thereto.

The stream of cracked products leaves the cracking zone through line 44 having a pressure reducing valve 46 and is preferably mixed with cracked products coming from the other cracking zone or coil 14 later to be described in more detail. The combined stream including the cracked products from the cracking zone 12 is passed under lower pressure into the evaporator or separating zone 52 of the combined evaporator and fractionating tower 16 where a separation into hot vapors and cracked residue takes place. The cracked residue is withdrawn through line 22 and may form part of the oil which is burned in the combustion zone 10.

The vapors separated in the evaporator or separating zone 52 are passed upwardly into the fractionating section 53 of the combined evaporator and fractionating tower 16 where they intimately contact fresh feed comprising a relatively heavy oil introduced into the fractionating section 53 through line 54. Some of the hot vapors are condensed to form heavy reflux condensate and some of the lighter constituents of

the heavy oil are vaporized. The unvaporized fractions of the heavy oil and the heavy reflux condensate are collected on trapout tray 56 having a hood 58, the trapout tray being located at the bottom of the fractionating section 53 of the combined evaporator and fractionating tower 16. If desired, however, the fresh feed may be introduced directly into the latter passes of cracking zone 12, after a suitable amount of preheating, through line 59, in which case a suitable reflux is introduced into the combined evaporator and fractionating tower 16 through line 60 in order to preserve the proper quality of the vapors passing through line 61. If desired, only part of the fresh feed may be introduced into the latter passes of the cracking zone 12 and the rest introduced into the combined evaporator and fractionating tower.

The unvaporized fractions of the heavy oil and the heavy reflux condensate are withdrawn from the trapout tray 56 and are passed through line 62 by pump 64. The stream of oil passing through line 62 is combined with oxygen or an oxygen-containing gas introduced through line 65 and a portion of the heavy oil is burned in order to raise the temperature of the unconsumed heavy oil. The hot products of combustion and unconsumed heated heavy oil are passed through the coil or zone 14 maintained under appropriate cracking conditions to effect the desired degree of cracking of the oil. In the preferred method of operation the proportion of oxygen, the temperature and the time of digest in the zone 14 are controlled to give the greatest reduction in viscosity of the residual constituents of the feed and to produce the greatest amount of comparatively low boiling range gas oil suitable for further cracking or for withdrawal as a product. While it is preferred to use the coil 14 which is not externally fired, in some instances it may be desirable to provide a furnace or a heater for the coil 14 to supply additional heat externally thereto. The coil 14 may be used to viscosity break heavy oils other than the heavy oil taken from the fractionating section 53.

After passing through the zone or coil 14, the hot products of combustion and cracked products may be passed through line 66 to a separator 68 and a cooling oil may be introduced through line 69. In the separator 68 there is a separation into hot vapors which are passed through line 72 having pressure reducing valve 73 into the evaporator or separating zone 52 of the combined evaporator and separating tower 16, and liquid residue which is withdrawn from the bottom of the separator 68 through line 74 by pump 76. The liquid residue may then be passed through line 78 having a pressure reducing valve 82 and mixed with the stream of cracked products leaving the cracking zone 12 through line 44 to effect further mild cracking or viscosity breaking of the liquid residue. This latter combined stream is then introduced into the evaporator or separating zone 52 of the combined evaporator and fractionating tower 16 wherein a separation into hot vapors and cracked residue occurs as has been above described. Lines 66 and 78 are provided with valves so that the separator 68 may be bypassed in which event the products from the cracking coil 14, preferably quenched, are passed directly through line 78 into evaporator 52. The separator 68 may be provided with the necessary internal fractionating equipment to serve as an efficient fractionator for the production of gas oil as side streams,

such as at 83, for heating or Diesel oils or similar purposes.

Instead of passing all of the unvaporized portions of the heavy oil and heavy reflux condensate through line 62, I may pass all or part thereof through line 84 by pump 85 and introduce the unvaporized portions of the heavy oil and heavy reflux condensate into the latter passes of the cracking zone or coil 12, or if desired, into the soaker 42. By introducing the heavy oil into the latter passes of cracking zone or coil 12 or into the soaker 42, the temperature of the heavy oil is raised to effect viscosity breaking thereof while the cracking of the oil first introduced into the cracking zone 12 continues.

The vapors remaining after contact with the fresh feed oil introduced into the fractionating section 53 of the combined evaporator and fractionating tower 16 are passed through line 61 into the bottom portion of the secondary fractionating zone 18 wherein they pass upwardly and are subjected to further fractionation by means of cooling applied to the top of the secondary fractionating zone 18. During this fractionation the fresh gas oil constituents distilled from the fresh feed in fractionating section 53 along with unconverted gas oil collect at the bottom of the secondary fractionating zone 18 and form the stock withdrawn through line 40 and passed through the main cracking zone 12. Drawoff points 87 and 88 may be provided to permit the withdrawal of gas oil from the system for use as heating and Diesel oils or the like.

The vapors of the desired boiling range leave the top of the secondary fractionating zone 18 through line 90, are condensed by passing through condenser 92 and the distillate is collected in a receiver or drum 94. The distillate collected in the receiver or drum 94 comprises gasoline and water which may be separated in any suitable manner, the water being drawn off through valved line 96 and the gasoline withdrawn through line 97. The gases which are not condensed leave the top of the receiver or drum 94 through line 98 and are passed to a washing tower 110 into which water or any other suitable solution or medium is introduced through line 112. In the case of water the carbon dioxide present in the gases will be dissolved and the solution of carbon dioxide is withdrawn from the bottom of the tower 110 through valved line 114. The remaining gases are passed from the top of the tower 110 through valved line 116 and may be passed to a suitable recovery plant for the extraction of contained gasoline. All or a portion of these gases leaving the top of tower 110 may be used for cooling by being introduced into the combustion zone 10 through line 39 as above described. The use of comparatively pure oxygen for heating in the coil 14 and combustion zone 10 has the advantage of producing no combustion products other than carbon dioxide and water which can be readily separated out before the remaining gases go to the recovery plant thus simplifying the stripping of the gases in the final steps of the process.

A portion of the gasoline collected in the receiver 94 may be passed through line 118 by pump 119 into the upper portion of the secondary fractionating zone 18 as reflux. As additional reflux some of the liquid near the top of the secondary fractionating zone may be withdrawn through line 120 by pump 122 and passed through heat exchanger 124 and then returned to the top of the secondary fractionating zone 18 through

line 126. The heat exchanger 124 serves to preheat the fresh feed passing through line 54 prior to its introduction into the fractionating section 53 of the combined evaporator and fractionating tower 16.

The fresh feed is passed through line 54 by pump 132 and after being preheated in heat exchanger 124 is further preheated by passing through heat exchanger 134. The preheated fresh feed is then passed through line 54 into the fractionating section 53 of the combined evaporator and fractionating tower 16.

The part of the cracked residue not used for burning in combustion zone 10 may be combined with the liquid residue passing through line 36 from the separator 35 and passed through heat exchanger 134 for preheating the fresh feed. The combined residue is then passed through cooler 136 and line 138 to a suitable receiver.

The pump 32 is provided to pump the oxygen or oxygen-containing gas through lines 28 and 65 to the combustion zone 10 and cracking coil 14.

An example of a typical operation contemplated by my invention will now be given but I am not to be restricted thereto. The fresh feed, such as reduced crude oil or other oil, preferably preheated to a temperature of about 250° to 550° F., is introduced into the top portion of the fractionating section 53 where it contacts the hot vapors therein. The unvaporized fractions of the heavy oil and the heavy reflux condensate are withdrawn from the bottom of the fractionating section 53 at a temperature of about 700° to 800° F., and are mixed with about 2.7 to 3.0 per cent by weight of oxygen or equivalent amount of oxygen-containing gas. A part of the heavy oil mixture is consumed by passing through coil 14 and the temperature of the unconsumed oil is raised sufficiently high to effect mild cracking or viscosity breaking thereof. The mixture of hot combustion products and unconsumed oil during its passage through the cracking zone or coil 14 is maintained under superatmospheric pressure of about 100 to 1000 pounds per sq. in. and a temperature of about 850 to 950° F. for a sufficient time to effect the desired extent of viscosity breaking of the oil.

If the unvaporized fractions of the heavy oil and heavy reflux condensate collected on trapout tray 56 are passed through line 84 and through the latter passes of the cracking coil or zone 12 instead of through the cracking zone 14, they are maintained under superatmospheric pressure of about 400 to 1000 pounds per sq. in. and at a temperature of about 850 to 950° F. for a sufficient time to effect the desired extent of viscosity breaking thereof.

Cracked residue is withdrawn from the bottom of the evaporator or separating zone 52 of the combined evaporator and fractionating tower 16 through line 22 and a portion of this residue is partially or completely burned in the combustion zone 10. The combined evaporator and fractionating tower 16 is preferably maintained under superatmospheric pressure, for example, about 50 to 100 pounds per sq. in. and the cracked residue under these conditions will be at a temperature of about 750° to 850° F. The desired portion of the cracked residue is mixed with about 320% by weight of oxygen or equivalent amount of oxygen-containing gas and burned by passing through the combustion zone 10. The proportions of oxygen or oxygen-containing gas and oil to be burned are preferably chosen so that substantially all of the cracked residue will be con-

sumed during the burning. The cracked residue withdrawn from the evaporator 52 is at a relatively high temperature and when it is combined with the oxygen or oxygen-containing 5 gas, an instantaneous rise in temperature results, the effect of which on the oil may be regulated by the size of the contacting zone as well as the proportion of oil and oxygen. By using a smaller proportion of the oxygen-containing gas, only a part of the cracked residue will be consumed and a lower temperature will be obtained.

After passage through the combustion zone 10 the products are passed to the separator 35 where 15 vapors are separated from any liquid residue. The liquid residue is withdrawn through line 36 and is preferably introduced into the line 22 subsequent to the point of withdrawal of a portion of the cracked residue through line 24. The 20 vapors and hot combustion products from the separator 35 at a temperature of about 1500° to 4000° F. are passed to the cracking zone or coil 12 where they are mixed with the oil to be cracked.

25 The oil to be cracked is preferably the condensate oil withdrawn from the bottom of the secondary fractionating zone 18 which is preferably maintained under superatmospheric pressure, for example, about 50 to 100 pounds per sq. in. and under these conditions the condensate oil will be at a temperature of about 550° to 700° F. The condensate oil to be cracked and the hot vapors and combustion products leaving the separator 35 are admixed and the mixture is passed 30 through the cracking zone 12 which is maintained under a high temperature of about 825° to 1125° F. and a superatmospheric pressure of about 400 to 1000 pounds per sq. in. for the desired time to effect the desired cracking of the oil.

40 The stream of cracked products is passed from the cracking zone 12 through the soaker 42 into the separating zone 52 of the combined evaporator and separating tower 16 which is under less pressure than the cracking zone 12 and where a 45 separation into vapors and cracked residue takes place. Before being introduced into the evaporator or separating zone 52, the stream of cracked products from the cracking zone 12 may be mixed with the cracked products leaving the cracking zone 14, or the stream may be passed directly to the evaporator or separating zone 52.

Known processes in which a large body of oil 55 in a vessel is treated with air are subject to the objection that coking occurs around the air nozzles mounted within the body of oil. After building up to a certain height, pieces of the deposited carbon break off and deflect the air stream. The coke then burns and in this burning localized overheating occurs which is a hazard to the apparatus in which the process is carried out. According to my process the burning of the oil takes place in a confined passageway such as a coil, for example, and objectionable coking with 60 its accompanying hazards is overcome.

70 In my invention air or oxygen-containing gas or the like is introduced into a stream of oil passing through the zone 14 by a nozzle so that there is a continuous passage of oil past the nozzle and the passageway is kept open by the continuous movement of the oil through the zone. If there is any coke formation, it will not be sufficient to stop or impair the operation of the process and if any pieces of the coke break off they will be 75 carried along with the oil stream and will not

cause local overheating of a portion of the apparatus. Generally, exceedingly high temperatures will be obtained in combustion zone 10 and there will be no objectionable deposition of coke therein. The use of an oxygen-containing gas richer in oxygen than air, moreover, has a tendency to prevent the objectionable deposition of coke because of high combustion temperatures which prevail and form the complete and instantaneous burning of the oil without the formation of decomposition intermediates which are the source of coke formation.

From the foregoing it will be apparent that I have disclosed a new process for converting oils which overcomes the objectionable features of prior known processes.

While I have described a particular embodiment of my invention, it is to be expressly understood that my invention is not restricted thereto, and various modifications and adaptations thereof may be made without departing from the spirit of my invention.

I claim:

1. A process for converting higher boiling hydrocarbons into lower boiling products that comprises separating resulting cracked products of the process into vapors and residue in a separating zone, passing resultant separated vapors to a fractionating zone into which charging stock is introduced and wherein fractionation takes place to form separated vapors and a fraction comprising unvaporized charging stock and reflux condensate, passing the separated vapors to a secondary fractionating zone wherein the vapors are subjected to fractionation to form a secondary reflux condensate, withdrawing separated residue from the separating zone, conducting residue so withdrawn to a contacting zone, introducing an oxygen-containing gas into said contacting zone to effect combustion of at least a portion of the cracked residue, combining resultant gaseous products of combustion with said secondary reflux condensate and passing the mixture through an elongated passageway of restricted cross section maintained under superatmospheric pressure to thereby subject the secondary reflux condensate to cracking temperature and effect conversion into lower boiling products, introducing said fraction comprising unvaporized charging stock and reflux condensate to a latter section of said elongated passageway to thereby subject said fraction to cracking, and directing resultant cracked products into said separating zone.

2. A process for converting higher boiling hydrocarbons into lower boiling products that comprises separating resulting cracked products of the process into vapors and residue in a separating zone, passing resultant separated vapors to a fractionating zone into which charging stock is introduced and wherein fractionation takes place to form separated vapors and a fraction comprising unvaporized charging stock and reflux condensate, withdrawing separated residue from the separating zone, conducting residue so withdrawn to a contacting zone, introducing an oxygen-containing gas into said contacting zone to effect combustion of at least a portion of the cracked residue, combining resultant gaseous products of combustion with condensate oil to be cracked and passing the mixture through an elongated passageway of restricted cross section maintained under superatmospheric pressure to thereby subject the condensate oil to cracking temperature and effect

conversion into lower boiling products, introducing said fraction comprising unvaporized charging stock and reflux condensate to a latter section of said elongated passageway to thereby subject said fraction to cracking and directing resultant cracked products into said separating zone.

3. A process for converting higher boiling hydrocarbons into lower boiling products that comprises separating resulting cracked products of the process into vapors and residue in a separating zone, passing resultant separated vapors to a fractionating zone wherein the vapors are subjected to fractionation to separate out a condensate, withdrawing separated residue from the separating zone, conducting residue so with-

drawn to a contacting zone, introducing an oxygen-containing gas into said contacting zone to effect combustion of at least a portion of the cracked residue, combining resultant gaseous products of combustion with said condensate and passing the mixture through an elongated passageway of restricted cross section maintained under superatmospheric pressure to thereby subject the condensate to cracking temperature and effect conversion into lower boiling products, introducing a residual stock to a latter section of said elongated passageway to thereby subject it to cracking and directing resultant cracked products into the first mentioned separating zone.
